CLAIM

The ornamental design for a combined bib and container pouch, as shown and described.

DESCRIPTION

FIG. 1 is a perspective view of a combined bib and container pouch showing my new design;

FIG. 2 is a top plan view thereof;

FIG. 3 is a bottom plan view thereof;

FIG. 4 is a front elevational view thereof;

FIG. 5 is a right side elevational view thereof;

FIG. 6 is a rear elevational view thereof;

FIG. 7 is a left side elevational view thereof;

FIG. 8 is a perspective view thereof; the container pouch shown flattened.

The broken line showing of the cup and straw in FIGS. 1, 2, and 4-7 is for illustrative purposes only.

FIG. 1

FIG. 2
